CONRAD RODER, OF PHILADELPHIA, PENNSYLVANIA, ASSIGNOR TO HIMSELF, WILLIAM S. WEIL, AND JACOB LOWENSTEIN, OF SAME PLACE.

Design No. 3,526, dated June 1, 1869.

DESIGN FOR A GENTLEMAN'S SCARF.

The Schedule referred to in these Letters Patent and making part of the same.

To all whom it may concern:

Be it known that I, CONRAD RODER, of the city of Philadelphia, in the State of Pennsylvania, have originated and designed a new Pattern for Gentlemen's Scarfs, of which the following is a full, clear, and exact description, reference being had to the accompanying drawings, making part of this specification.

The design herein referred to for gentlemen's scarfs is intended for that kind of fabric known as the "honey-comb fabrics," and consists of certain figures, or an arrangement of figures and honey-comb spaces, as is fully shown by the drawings herewith annexed.

What I claim as my invention, and desire to secure by Letters Patent, is—

The design or pattern, herein set forth and shown, for gentlemen's scarfs.

CONRAD RODER.
